US00D627670S

(12) **United States Design Patent**
Gonzales

(10) **Patent No.:** **US D627,670 S**
(45) **Date of Patent:** **** Nov. 23, 2010**

(54) **HAZARDOUS CONDITION DETECTOR**

2010/0117840 A1 * 5/2010 Rutter et al. 340/628

(75) Inventor: **Eric V. Gonzales**, Aurora, IL (US)

(73) Assignee: **Universal Security Instruments Inc.**,
Owings Mills, MD (US)

(**) Term: **14 Years**

(21) Appl. No.: **29/351,136**

(22) Filed: **Dec. 1, 2009**

(51) **LOC (9) Cl.** **10-04**

(52) **U.S. Cl.** **D10/81**; D10/106

(58) **Field of Classification Search** D10/81,
D10/106; 73/23.25; 340/628, 629, 630,
340/632, 691.5, 693.5; 422/86, 94; 702/24

See application file for complete search history.

(57) **CLAIM**

The ornamental design for a hazardous condition detector, as shown and described.

DESCRIPTION

FIG. 1 is a perspective view of the hazardous condition detector according to the present invention.

FIG. 2 is a top view of the hazardous condition detector according to the present invention.

FIG. 3 is a bottom view of the hazardous condition detector according to the present invention.

FIG. 4 is a first side view of the hazardous condition detector according to the present invention.

FIG. 5 is a second side view of the hazardous condition detector according to the present invention.

FIG. 6 is a third side view of the hazardous condition detector according to the present invention; and,

FIG. 7 is a fourth side view of the hazardous condition detector according to the present invention.

The broken line showing of structural features is included for the purpose of illustrating non-claimed subject matter and forms no part of the claimed design.
